UNITED STATES PATENT OFFICE.

WILLIAM V. ROBINSON, OF OWOSSO, MICHIGAN, ASSIGNOR TO THE INDEPENDENT STOVE CO., OF OWOSSO, MICHIGAN, A CORPORATION OF MICHIGAN.

GAS BURNER.

Application filed February 27, 1922. Serial No. 539,364.

To all whom it may concern:

Be it known that I, WILLIAM V. ROBINSON, a citizen of the United States of America, residing at Owosso, in the county 5 of Shiawassee and State of Michigan, have invented certain new and useful Improvements in Gas Burners, of which the following is a specification, reference being had therein to the accompanying drawings.

10 The invention relates to gas burners more particularly designed for use on open top gas ranges and the invention consists in the novel construction as hereinafter set forth.

15 In the drawings:

Figure 1 is a longitudinal section through the burner;

Figure 2 is a top plan view thereof.

20 Figure 3 is a cross-section on line 3—3 of Figure 2.

In the use of gas stoves and ranges there is a great fluctuation in the pressure at which the gas is delivered at different times. Consequently, an adjustment of the burner 25 which is satisfactory for one pressure is not as good for a higher or lower pressure. In particular, where, as is usually the case, the gas jets are directed upward, there must be sufficient space between the burner and 30 the vessel to be heated so as not to interfere with combustion. If the gas pressure is strong, a greater distance is required than where the gas pressure is weak. On the other hand, if the height of the vessel 35 above the burner is proper for strong pressure with a weak pressure, the heating effect will be greatly reduced.

It is the primary object of the present invention to obtain a construction where a 40 variation in gas pressure will not require any change in the distance between the burner and the vessel to be heated and also one where in the lowest pressure an efficient heating effect is produced. This I 45 have accomplished by forming the burner

with an imperforate top and with the gas jets directed laterally in a plane slightly below the top.

In detail, A is a gas burner provided with the mixing tube B and a series of 50 radially projecting arms C forming the burner proper. Each of these arms C is formed of a wedge-shaped cross-section with an imperforate top D and laterally extending jet apertures E slightly beneath 55 said top. At the center the inner ends of the arms C merge into each other and at the center there is an aperture F for a supply of air from beneath the burner. With the construction as just described, when the 60 burner is in operation, the jets will all be directed laterally and, therefore, increase or decrease in gas pressure will only change the length of these jets without materially changing the distance between the jets and 65 the top plane of the burner. The burner is therefore placed in the range so as to be but a short distance below the bottom of the vessel to be heated and the flame, whether the jet is large or small, will be in 70 close proximity to the vessel. The arms C being of a wedge-shaped form, or greater in width at the bottom than at the top, has the effect of shielding the flames from too strong an air draft. Therefore, in operation, satisfactory results may be obtained 75 under very different pressure conditions of the gas.

What I claim as my invention is:

80 A one piece burner comprising a series of radially extending arms connected together at their inner ends, each of said arms having a rounded bottom and a flat top, the sides of each arm tapering gradually upward from the rounded bottom to the flat 85 top and having a plurality of openings therein for directing the flames laterally.

85 In testimony whereof I affix my signature.

WILLIAM V. ROBINSON.
